UNITED STATES PATENT OFFICE.

MARK K. MAYNARD, OF COLTON, WASHINGTON.

WINDOW LOCK.

Application filed January 21, 1924. Serial No. 687,538.

To all whom it may concern:

Be it known that I, MARK K. MAYNARD, a citizen of the United States, residing at Colton, in the county of Whitman and State 5 of Washington, have invented certain new and useful Improvements in Window Locks, of which the following is a specification.

This invention relates to improvements in window locks, and has for its primary object to provide such a lock, wherein the window may be positively maintained against upward or downward movement in a partly opened or closed position.

A further object of the invention is to 15 provide such a window lock that may be applied to practically all types of window frames wherein there are positioned sliding sashes, in a novel, simple, and expeditious manner.

20 A still further object of the invention is the provision of such a window lock, that is extremely efficient in operation, and highly useful for the purposes intended.

The nature and advantages of the invention will be better understood when the following detailed description is read in connection with the accompanying drawing, the invention residing in the construction, combination, and arrangement of parts as 25 claimed.

In the drawing forming part of this application, like numerals of reference indicate similar parts in the several views, and wherein:

30 Figure 1 is a fragmentary sectional view, through a window frame equipped with my improved lock, which lock is shown partly in side elevation, and partly in cross section.

40 Figure 2 is a fragmentary plan view of the inner side of the window frame that carries my improved lock, together with said lock, and

45 Figure 3 is a perspective of one of the wing-shaped spring pressed jaws, that is included in my lock.

Now, having particular reference to the drawing, 5 designates generally a window frame, and 6 one of the sliding sashes within said window frame.

50 My novel lock comprises a suitable form of casing 7 that is open at its inner edge, and positioned within an opening of the frame 5, and in longitudinal alinement with

said sash 6. The inner side of said frame 55 surrounding said opening is mortised for the reception of a lock plate 8, that is maintained in position by wood screws 9, and that is formed with a pair of spaced oblong openings 10, for purposes presently to be 60 set forth.

Within the lock casing 7 adjacent the open edge thereof, and in vertical alinement with each other is a pair of wing-shaped jaws 11, the outer edges of which are 65 toothed at 12 in reverse directions to each other. As more clearly shown in Figure 3, each of the said jaws 11 is formed with a circular head 13 upon the opposite ends of which are pintles 14 for engagement within 70 openings of the side walls of the casing 7, whereby the same have free swinging movement within the casing towards and away from the adjacent edge of the frame of said sash 6. 75

Each of the jaws 11 are channeled upon its inner side at 15, and surrounding the portion of the head 13 of said jaws coextensive with the channel 15 is a spring 16, one end of which has engagement with the 80 edge of the channel, the opposite end having engagement with the adjacent side of cross guides 17, whereby these jaws are normally maintained in the position of Figure 1, that is, in engagement with the adjacent side of the sash frame, for preventing the raising or lowering of the sash. 85

Slidable between the said guide plates 17 is a head 18, the front end of which is curved for engagement with the adjacent 90 portions of the jaws 11. The opposite end of this head is notched as shown in Figure 1, for receiving the bent end of a finger 19, that is carried by a shaft 20, and extends through openings in the side walls of the 95 casing 7, as well as extending through an opening in the window frame 5, and projecting outwardly thereof for receiving a key 21, whereby said shaft may be rocked.

It will be apparent from the above description when considered in conjunction with the accompanying drawing that the jaws 11 are normally in the position shown, that is, extending through said openings 10 in the plate 8, and having engagement with the adjacent side of the frame of the sash 6, for preventing the sash from being raised or lowered. A turning of the shaft 20 in 100 105

one direction will occasion a forward movement of the head 18 for consequently swinging the jaws 11 upon their pivots and thereby retracting the same within the casing 7 for allowing the sash to be raised or lowered.

Numerous advantages of a window lock of this character will be readily appreciated by those skilled in the art, and although I have herein shown and described the preferred embodiment of the invention, it is nevertheless to be understood that minor changes may be made therein, without departing from the spirit and scope of the invention as claimed.

Having thus described my invention,

what I claim as new, and desire to secure by Letters Patent, is:

A window lock comprising a casing, guide plates located therein, a head mounted for sliding movement between the guide plates, jaws pivotally mounted in the casing and having end portions passing through the side of the same and having inner end portions engaging the head, springs coiled around the pivots of the jaws and engaging the guide plates and the jaws and a shaft journaled in the casing and having a finger engaging the head.

In testimony whereof I affix my signature.

MARK K. MAYNARD.
